EVAPORATOR AND SHELF

**Franklin G. Slagel, Buffalo, N. Y., assignor to
Fedders Manufacturing Company, Inc., Buffalo,
N. Y., a corporation of New York**

Application December 31, 1931
Serial No. 584,213

2 Claims. (Cl. 62—126)

This invention relates to mechanical refrigerating systems and more particularly to evaporators with refrigerated shelf means.

It is the general practise to provide refrigeration evaporators with a freezing chamber in which is arranged shelf means for increasing the food supporting surface. In order to accelerate the rate of heat transfer from food supported in the evaporators, it has been heretofore proposed to circulate the refrigerant adjacent the shelf means.

An object of the invention is to provide a new and novel form of refrigerated shelf for evaporator chambers.

Another object of the invention is to provide a
15 refrigerated shelf which is connected with an
evaporator so that the duct means of the shelf
forms a part of the circulating system through
which refrigerant must travel in passing from
the evaporator.

20 A further object of the invention is to provide a refrigerated shelf for evaporators which can be economically fabricated and associated with an evaporator.

Other objects of the invention will appear from the following description taken in connection with the drawing, which forms a part of the specification, and in which:

Fig. 1 is a side elevation of an evaporator with a refrigerated shelf therein incorporating the invention.

Fig. 2 is a plan view of the same.

Fig. 3 is a front elevational view of the same.

Fig. 4 is a plan view, partially broken away, showing the refrigerated shelf removed from the evaporator.

Fig. 5 is a perspective view of the evaporator and another form of refrigerated shelf, looking at the rear end.

Fig. 6 is a sectional view of the modified form 40 of shelf taken on line 6-6 of Fig. 5.

Referring now to the drawing by characters of reference, 10 represents generally an evaporator formed of two sheets of metal 11 and 12 bent to

formed of two sheets of metal 11 and 12 bent to form an enclosed open end chamber for the storage of food or liquid. The inner sheet of metal is flat, while the outer sheet of metal is formed with a pressed out rib 13 forming with the adjacent inner sheet a continuous duct means 14. The duct means extends from the rear to the front of the evaporator in parallel loops which surround the chamber. The two sheets of metal are welded together at the front and rear ends of the abutting edges, as indicated at 15, and along the junction of the abutting edges, as indicated at 16. The sheets are also welded together along

each side of the conduit means in order to seal the same as a conduit. A refrigerant inlet nipple 17 extends from the outer wall at one end of the evaporator, while a refrigerant outlet nipple 18 extends from the outer wall at the other end of the evaporator.

The duct means around the evaporator is interrupted adjacent the outlet end, and connected therewith to complete the refrigerant circulatory system is means connected with the shelf 65

The shelf shown in Figs. 1 to 4 of the drawing is preferably formed of two sheets of metal 20 and 21 which are welded together along their edges, as indicated at 22, and the front end 23 of the top sheet is bent around the front end of the under sheet and welded thereto. The under sheet of the shelf is formed with a depressed serpentine rib 24 extending mainly lengthwise thereof. The sheets are welded along the sides of the depressed rib as indicated at 26 to seal 75

the depressed ribs, as indicated at 26, to seal the conduit or duct means formed by the rib and the adjacent portion of the overlying sheet. The rear end 27 of the shelf is bent upwardly and the under sheet is formed with a pair of longitudinally extending pressed out ribs 28 and 19 which communicate with the end of rib 24 and form connecting means with the interrupted portion of the conduit or duct means around the evaporator. This upturned end also serves to form a partial rear wall for the evaporator chamber. The turned under front end of the top sheet of the shelf is turned down to form a

sheet or the shelf extends beyond the shelf proper and forms legs 29 which are welded, or otherwise secured, to the inner wall of the evaporator. The interrupted ends 30 and 31 of the evaporator duct means terminate in nipples into which forwardly extending nipples 32 and 33 of the shelf back telescope and are soldered or welded to form a leak proof seal, the nipples 32 and 33 being formed at the ends of the ribs 28 and 19 from the outer sheet of the shelf back. As shown in Fig. 4, the rear end of the sheets forming the shelf are welded together on both sides of the nipples and the inner sheet is cut out to receive the nipples of the outer sheet. A portion of the end of the evaporator sheet is cut out, as indicated at 34, to receive the portion of the shelf sheet on which the nipples 32 and 33 are formed.

The evaporator is adapted to form a part of a conventional compressor-evaporator-condenser refrigerating system, and the nipple 18 is connected with the compressor and the nipple 17 is connected with the condenser. Refrigerant flows into the nipple 17 and around the evaporator duct means, then through the duct 28 into the 110

duct means in the shelf proper. Refrigerant flows through the duct means 19 and into the evaporator outlet duct means and nipple 18. It will thus be seen that the shelf forms an intermediate portion of the refrigerant circulatory system of the evaporator, and that all refrigerant passing into the evaporator must flow through the shelf before leaving the evaporator.

In Figs. 5 and 6, I have shown another form 10 of refrigerated shelf. In this instance, the shelf is formed of two sheets of metal 40 and 41, the upper sheet being flat and having extended arms 42 which are welded or otherwise secured to the inner wall of the evaporator. The under sheet 15 is formed with a depressed serpentine rib 43 which extends mainly longitudinally of the shelf and the ends thereof are at the rear and terminate in nipples 44 and 45. The sheets are welded together around their edges, as indicated 20 at 46, and also along the sides of the depressed rib or duct means. A pair of hollow legs 47 and 48 telescope into the nipples 44 and 45 respectively providing refrigerant inlet and outlet means for the duct means in the shelf as well as a support 25 for the shelf.

The evaporator with which this form of shelf is associated is similar to that previously described and the inlet nipple for the evaporator duct means is at the front and the outlet nipple 30 is at the rear. The duct means is interrupted at the rear duct loop and the interrupted portion terminates in spaced nipples 49 and 50 extending upwardly from the inner wall of the evaporator so that the hollow supporting legs can be telescoped therein. The refrigerant in this instance flows into the inlet nipple 17, through the duct means to the leg 47, through the duct means in the shelf and then through the leg 48 to the

outlet end of the rear leg 49 of the evaporator duct means and out through the nipple 18.

It will be seen that the shelf means can be economically fabricated, and that the refrigerant in passing through the evaporator must flow 80 through the shelf means, thus accelerating heat transfer from the material supported on the shelf or contained in the refrigerated chamber.

Although the invention has been described in connection with certain specific embodiments, 85 the principles involved are susceptible of numerous other applications which will readily occur to persons skilled in the art, and the invention is therefore to be limited only as indicated by the scope of the appended claims.

What I claim is:

1. In an evaporator for a refrigerant system, a housing having duct means forming a freezing chamber, a shelf comprising a pair of superimposed connected sheets of metal formed with a serpentine duct therebetween, said shelf having a rectangular portion mounted in said chamber to form an ice tray mounting and an angular terminal portion forming a partial rear wall for the chamber, and means connecting the housing duct means to the shelf duct for fluid communication.

2. In an evaporator for a refrigerant system, a housing having duct means forming a freezing chamber, a shelf having a serpentine duct therein, said shelf having a portion extending horizontally in said chamber to form an ice tray mounting and a bent terminal portion extending angularly thereto and forming a partial rear wall for the chamber, and means connecting the 105 housing duct means to the shelf duct for fluid communication.

FRANKLIN G. SLAGEL.
